No. 857,442.

PATENTED JUNE 18, 1907.

T. A. B. CARVER,
LEASE ROD FOR LOOMS, WARPING MACHINES, AND THE LIKE.
APPLICATION FILED SEPT. 28, 1905.

UNITED STATES PATENT OFFICE.

THOMAS ALBERT BRIGGS CARVER, OF GLASGOW, SCOTLAND.

LEASE-ROD FOR LOOMS, WARPING-MACHINES, AND THE LIKE.

No. 857,442.

Specification of Letters Patent.

Patented June 18, 1907.

Application filed September 28, 1905. Serial No. 280,507.

To all whom it may concern:

Be it known that I, THOMAS ALBERT BRIGGS CARVER, a subject of the King of Great Britain, residing at 33 Renfield street, 5 in Glasgow, Scotland, civil engineer, have invented certain new and useful Improvements in Lease-Rods for Looms, Warping-Machines, and the Like, of which the following is a specification.

Breakages of the yarn in looms, warping machines or the like are liable to occur when the threads passing above and below the lease rods adhere together owing to the dressing of the warp or from any other cause. By 10 this invention these breakages are diminished by constructing the lease rods in such a manner that they can expand and contract in a direction at right angles to the plane of the warp, so that the surfaces against which 15 the threads lie on the rod above and below it, or on one side of it and the other, can move relatively to each other in obedience to the periodic variations of tension in the warp. For instance, the rod may be divided longitudinally and the two parts connected together by suitable springs, the threads of the warp lie respectively against the top polished surface and against the bottom polished surface 20 of this compound rod, in the case of a horizontal lease rod, and the rod contracts and expands as the warp is tightened and loosened. Or the rods may have separate surfaces connected by springs which term includes devices depending on fluid pressure. 25 The invention is particularly applicable to looms or warping machines which are fitted with warp stop motions more particularly a warp stop motion of the kind described in the specification to U. S. Letters Patent No. 35 740672.

In the accompanying drawings Figure 1 is a perspective view of a lease rod made according to the invention; Fig. 2 is a cross section and Fig. 3 a side elevation of a modification of the rod; and Fig. 4 is a vertical section through a part of a loom provided with a warp stop motion according to the aforesaid specification and a lease rod according to this invention.

In all the figures like reference letters indicate like parts.

The lease rod is made in two parts, *a* and *b*, connected together by springs *c* which may

be laminar springs as shown in Fig. 1 or helical springs as shown in Figs. 2 and 3. The threads pass over and under this compound rod as indicated by *d* in Fig. 2, and the surfaces against which they rest may be polished. The expansive medium between the sections of the lease rod expands as will be apparent upon an inspection of the drawings on a straight line instead of on a curved line. This expansive medium in the present case consists of several springs as will be understood from what has been stated. 65

When the lease rod is applied in conjunction with a warp stop motion it need only be used as the rod over which the warp first passes, because it is at this point that the opening of the warp is particularly required. This is 70 shown in Fig. 4 where the warp *d* moves in the direction of the arrow and passes first over the expanding lease rod and then over an ordinary lease rod *e*. The wire *f* is fixed at its lower end to a suitable beam *g* and is 75 held at its upper part in front of the crossing of two of the warp threads. If either of these threads breaks the wire springs back and serves either to indicate to the attendant that the machine is to be stopped or to actuate 80 electrically or mechanically some stopping device.

As the tension in the warp increases and diminishes periodically with the cycle of the loom, the two parts *a* and *b* of the lease rod 85 approach and recede from each other, and this movement greatly assists in separating threads which may be adhering together owing to the dressing or from any other cause.

It will be evident that the sections or 90 parts of my lease rod are separated. In other words there is no direct connection between the two, such as is presented by a hinge. I interpose an expansive medium between the parts or sections of said rod 95 which normally or constantly tends to spread them apart. By virtue of the construction described said sections can bodily approach and recede from each other in parallelism so that there is no tendency when they are 100 spread apart of their abrading the warp. When I speak of the rod sections or parts as separated, I mean to convey the idea that they are separated throughout the length thereof traversed by the warp. 105

Having thus described the nature of my

said invention and the best means I know of carrying the same into practical effect, I claim:—

5 A lease rod having sections and an expansive medium therefor serving to positively spread said sections apart and maintain the same in parallel planes.

In testimony whereof I have signed my name to this specification in the presence of two subscribing witnesses.

THOMAS ALBERT BRIGGS CARVER.
